[57] CLAIM

The ornamental design for a package for a plurality of bottles as shown and described.

DESCRIPTION

FIG. 1 is a top plan view of a package for a plurality of bottles showing my new design;

FIG. 2 is a bottom plan view thereof;

FIG. 3 is a side view thereof; the other side is a mirror image thereof;

FIG. 4 is an end view thereof; the other side is a mirror image thereof;

FIG. 5 is an enlarged partial cross section view taken along line 5—5 of FIG. 1;

FIG. 6 is a bottom perspective view thereof; and,

FIG. 7 is a top perspective view thereof.

It is to be understood that in each of FIGS. 1 and 2 the design is continuous and repeating over the entire surface so that the internal design is common throughout the figure.
